UNITED STATES PATENT OFFICE

BENJAMIN R. HARRIS, OF CHICAGO, ILLINOIS

EMULSION

No Drawing. Application filed August 21, 1930, Serial No. 476,935. Renewed October 5, 1932.

My invention relates in general to improved emulsions and emulsion improving substances. It relates more specifically to an improved non-spattering type of margarine and anti-spattering substances for use with margarine.

By means of my new products I am able to impart superior qualities to many types of emulsions, particularly emulsions of fats and 10 oils used for culinary purposes, but I shall explain the same in connection with improvements in margarine. Those skilled in the art are referred to my prior application Serial Number 383,143, filed on August 2, 15 1929, for a more complete disclosure of certain details of the invention than is made herein. I wish also to call attention to my co-pending application Serial Number 475,622, filed on August 15, 1930, as a continuation in part of application Serial Number 383,143, filed August 2, 1929.

In general the present invention represents a specific embodiment of the main invention disclosed in the co-pending application above 20 referred to, and while the present disclosure is substantially complete in so far as it describes the invention and supports the claims, those interested in the art are referred to the co-pending case for a more complete disclosure of the basic concept of the invention.

The principal object of my present invention is to improve such forms of emulsion as margarine.

Another object is to reduce the spattering 35 of margarine when used for frying purposes and generally improve its frying behavior.

Other objects and features of the invention will be apparent from a consideration of the following detailed description.

As was disclosed in my prior applications I have discovered a large class of chemical compounds which may be used to impart improved characteristics to all types of water-oil emulsions, particularly those used for 40 cooking purposes, and other types of culinary fat preparations. These substances have several characteristics in common which make them very valuable in their use with margarine. These substances are compatible 45 with mild acids and in particular with lactic

acid in the concentration and under the conditions existing in margarine. They are difficultly soluble in oils and fats and aqueous media and in many cases are substantially insoluble. This makes it possible to use 55 those compounds in very small quantities, as they may be considered to concentrate at the water-oil interface of the emulsion rather than be dissolved in either the water or oil phase. These substances are semi-colloidal 60 or truly colloidal in character and are frequently colloidally dispersible in aqueous and/or oleaginous media. They are, moreover, substantially non-volatile at margarine frying temperatures and so will remain in 65 the margarine and perform their function during frying.

One of the most important characteristics of these compounds is the presence in the molecule of two types of groups in balanced 70 relation to each other, one group being hydrophylic or water wetting in character, and the other group being lipophylic or fat wetting in character. These groups must exist in the molecule in such a state of balance 75 that they will function at the water-oil interface in the intended manner. Presumably these substances orientate themselves at the interface, by reason of the balance of the two types of groups, but it is understood that the 80 invention does not depend upon this explanation.

My prior application treats exhaustively of the manner in which the balance between the two groups may be determined so that 85 without tests of any kind it is possible for the skilled colloid chemist to pick out compounds which can not function effectively as anti-spatterers, as well as compounds which clearly will be effective as anti-spatterers.

However, there are compounds of such character that the state of balance existing between the two groups in the molecule is 90 preferably determined by a simple quick test.

The balance of the hydrophile-lipophile groups in the compound which I apply in my invention is one of the characteristics and determinant of the class of substances which I employ.

The test which I have chosen as a means for determining the hydrophile-lipophile balance in organic compounds, I call the "spoon test". It is carried out as follows:

5 From 0.05 to 0.10 gr. of the material or substance in question is introduced into a porcelain mortar, wetted and ground into a smooth paste with a pestle with a minimum proportion of water; two to five drops generally 10 will suffice.

An ordinary margarine such for example as one made from vegetable oils, and fats and cultured skimmed milk and which possesses the usual property of spattering during frying is selected. Ten grams of this 15 margarine are then introduced in small portions into the mortar and macerated thoroughly with the paste first prepared until the entire ten gram portion is thoroughly and 20 uniformly intermixed with the material in the mortar. Two grams of this mixture are introduced into a tablespoon and held directly over a free flame such for example a Bunsen flame, one or two inches long, in such 25 a position that the point of the flame just about reaches the bottom of the spoon. A clean sheet of paper is placed on the bottom of the burner by inserting the stem of the Bunsen burner prior to lighting through a 30 hole made in the center of the paper and allowing the paper to drop to the base of the burner to catch the margarine splashed out during the heating. The mixture in the 35 spoon is heated until all of the water is boiled off and the ebullition ceases and the spots on the paper observed.

If this treated margarine spots the paper to the same extent as the untreated margarine from which the former was prepared, then 40 the lipophile and hydrophile groups of the compound are not balanced. The number and size of spots on the paper or the added weight can be readily determined.

If the increase in weight of the paper or 45 the number and character of the spots produced on the paper up until all the water has boiled off are less than that produced by similarly heating two grams of the original untreated margarine employed for the test, then the material or substance in question 50 has balanced hydrophile-lipophile groups. The expression "balanced lipophile and hydrophile groups" used in the claims is to be 55 interpreted in terms of the above described "spoon test".

My present invention relates to a specific

class of compounds in which the hydrophile function is exercised primarily by a phosphatic group, that is, a group containing phosphorus in the form of its oxygenated acid radicals. Preferably, the anti-spattering compounds of the present invention are entirely non-nitrogenous, but if they contain any nitrogenous group, it should be devoid of the nitrogenous linkage expressed in the following formula:

75
75

wherein "O" represents oxygen, "X" stands for phosphorus in the form of its oxygenated acid radicals such as phosphorus, etc., "C" represents carbon, "H" is hydrogen, "w" represents a small whole number, and "N" is trivalent or pentavalent nitrogen and the terminal oxygen indicated above is linked directly to carbon.

95

In my co-pending application, Serial No. 481,348 filed September 11, 1930, I describe and claim certain types of nitrogenous compounds which can be used with my invention. In my present application I am interested principally in compounds containing phosphorus.

95
95
95

Examples of some of the phosphatic materials which I have used as anti-spattering agents, many of them not known heretofore, are as follows:

125

130

Calcium triricinolein phosphite

15 It is to be noted that in every case, the anti-spattering agent has been produced by associating in a given molecule a lipophile group with a hydrophile group, wherein the hydrophile function is supplied primarily by a phosphorus containing radical. However, the conclusion must not be drawn from this that any random combination of a phosphorus containing radical or its metal derivative with a lipophile group will give an anti-spatterer.

20

25 Examples of molecules, with phosphorus containing hydrophile groups as well as lipophile groups, but which nevertheless are not anti-spatterers are as follows:

Class "A"

Class "B"

45 In the case of compounds of both Class "A" and Class "B", anti-spattering powers are lacking because of inadequate balance between the lipophile and hydrophile groups. In the case of compounds of Class "A", the hydrophile group dominates and is inadequately balanced by the lipophile group, that is, the lipophile characteristics of the latter are too weak to balance and coact with the hydrophile group. In the case of substances 50 of Class "B", the reverse situation exists and anti-spattering power is absent because the lipophile group is dominant and is inadequately balanced by the hydrophile group.

55 The examples of phosphatic anti-spatterers listed above, as well as other phosphatic substances which can be employed for the purpose which I have used successfully, I prepared by a number of different methods which are adequately described in the scientific and technical literature, and which

methods are readily available to skilled chemists.

The compounds described above are of unusual importance in connection with their use with water-oil emulsions of all kinds, but they have a particular adaptation for use with all culinary emulsion products such as margarine. Commercial margarine after being treated with my anti-spattering agent, when fried in a shallow pan exhibits improved frying behavior in that it allows its water to boil off quietly, fries in a pleasing and comparatively quiet manner with the formation of considerable turbid froth and foam after the manner of butter, reduces the tendency of the curd to stick to the bottom of the frying pan, and reduces the amount of material which escapes from the pan by spattering. Untreated margarine on the other hand when fried bumps turbulently, sputters noisily and foams comparatively little. Also what little foam there is, is transparent and of an entirely different character from that obtained from margarine previously treated with an anti-spatterer.

My emulsion improvers may be introduced in the margarine in a number of ways, as long as a satisfactory dispersion is obtained. For instance, the main constituents of margarine are edible oils and fats and cultured milk, and the anti-spattering or improving compounds may be introduced either into the oils or milk in any suitable manner. They may also be introduced into the churn during the production of the emulsion in its liquid state, care being taken to bring about the necessary dispersion. Or, the anti-spattering material may be used in a dry condition and mixed with the salt which is worked into the crystallized margarine, or the anti-spattering material may be made into a paste with milk and kneaded in, or blended into the margarine.

Generally speaking, the compounds which I am using in connection with this invention are: Phosphoric acid esters of high molecular weight organic compounds which will balance the phosphoric acid radical. It is to be noted that in each case the hydrophile group containing phosphorus is at or near an end of the molecule. These compounds may be represented structurally as follows

in which "O" is oxygen, "P" is phosphorus, "X" is an edible cation such as hydrogen, sodium, potassium, calcium, or the like, "Y" is either an edible cation or an organic radical, "w" is a small whole number and "R" is an organic lipophile group.

Thus, the above compounds may be phosphoric acid esters of a high molecular alcohol

uch as cetyl alcohol, or it may be a phospho-
ic acid ester of a polyalcohol and/or its sub-
stitution products such as, for example, a
phosphoric acid ester of glycol or diethylene
glycol in which one OH is esterified with a
higher fatty acid such as stearic acid, or com-
bined in an ether linkage with a high alcohol
uch as cholesterol. Thus, for example, a
phosphoric acid ester of stearyl diethylene
lycol, a phosphoric acid ester of monostearyl
lycerol, or a phosphoric acid ester of chole-
steryl-diethylene glycol.

As to the specific application of the in-
vention to margarine and other emulsions or
oleaginous culinary preparations, it is clear
hat since there are many phosphatic com-
ounds containing balanced hydrophile and
pophile groups, it is impractical and un-
necessary to list each particular combination
f groups which can be used in accordance
ith my invention. Moreover, while I leave
omething to the skill of persons applying
y invention, my description is wholly suffi-
ently exhaustive, particularly when consid-
red with respect to my prior applications,
enable those skilled in the art to success-
illy practise the same.

The term "non-spattering margarine" as
ed in the claims is employed to designate a
argarine, the frying behavior of which is
proved by the addition thereto of the nov-

el materials of my invention herein described.

The term "margarine" as employed in the
claims includes plastic emulsions of vege-
table or animal oleaginous substances or mix-
tures thereof, with aqueous materials such 70
as water, sweet or ripened milk, and with
or without coloring matter. Examples of
margarine within this definition, besides the
conventional margarine of commerce, are:
puff paste, renovated butter, and any like 75
fatty-aqueous compositions which may be
used in frying.

What I claim is new and desire to protect
by Letters Patent of the United States is:—

1. A non-spattering margarine, having an 80
oleaginous phase and an aqueous phase, and
having included therein a proportion of a
phosphoric acid ester of a higher molecular
weight alcohol having eighteen carbon atoms
or more in its radical, said compound having 85
balanced hydrophile and lipophile groups.

2. A non-spattering margarine, having an
oleaginous phase and an aqueous phase, and
having included therein a proportion of a
chemical substance having a lipophile group 90
in the form of a cholesteryl radical, and a
balancing hydrophile group containing phos-
phorus.

In witness whereof I hereunto subscribe
my name this 18th day of July, 1930.

BENJAMIN R. HARRIS.
